(57) **CLAIM**

The ornamental design for a power inverter, as shown and described.

DESCRIPTION

FIG. 1 is a front, left and top perspective view of a power inverter, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left and top perspective view of a second embodiment of a power inverter.

FIG. 10 is a rear, right and bottom perspective view of the second embodiment of the power inverter of FIG. 9.

FIG. 11 is a front elevation view of the second embodiment of the power inverter of FIG. 9.

FIG. 12 is a rear elevation view of the second embodiment of the power inverter of FIG. 9.

FIG. 13 is a left side elevation view of the second embodiment of the power inverter of FIG. 9.

FIG. 14 is a right side elevation view of the second embodiment of the power inverter of FIG. 9.

FIG. 15 is a top plan elevation view of the second embodiment of the power inverter of FIG. 9; and,

FIG. 16 is a bottom plan elevation view of the second embodiment of the power inverter of FIG. 9.

(Continued)

The broken lines depict portions of the power inverter that form no part of the claimed design.
